UNITED STATES PATENT OFFICE.

SOLOMON S. MOYER, OF ALLENTOWN, PENNSYLVANIA.

UNIVERSAL CLOCK.

SPECIFICATION forming part of Letters Patent No. 369,462, dated September 6, 1887.

Application filed February 19, 1887. Serial No. 228,270. (No model.)

To all whom it may concern:

Be it known that I, SOLOMON S. MOYER, a citizen of the United States, residing at Allentown, in the county of Lehigh, State of Pennsylvania, have invented certain new and useful Improvements in Universal Clocks, of which the following is a specification, reference being had therein to the accompanying drawings.

10 This invention has relation to clocks and other time-pieces; and the object in view is to provide a clock of ordinary construction, so far as the internal system of gearing is concerned, with additional devices which shall serve the purpose of indicating the time at various desired different points upon the earth's surface.

Another object in view is to provide the necessary devices for indicating the day of the month automatically.

20 Other objects and advantages of the invention will be hereinafter described, and the novel features thereof will be particularly pointed out in the claims.

Referring to the drawings, Figure 1 is a front elevation of a combined clock and calendar embodying my invention. Fig. 2 is a section taken on the line X of Figs. 1 and 3. Fig. 3 is a rear elevation showing the interior mechanism. Fig. 4 represents the new-date calendar operating lever depressed by the roller R before that of the old-date calendar, as hereinafter described.

Like letters refer to like parts in all the figures.

35 A represents any suitable casing or framework, having a glass, A', in the front thereof, and B represents the fixed portion of the dial, and C the movable portion thereof. A cross-bar, D, serves, with a frame, D', mounted thereon, the purpose of supporting the mechanism or gearing employed.

The movable dial C represents the globe, and is divided by lines of longitude C', and upon any suitable line or between any suitable lines of longitude certain points may be selected for the location of local dials, C².

Local dials are shown for London, Berlin, Pekin, China, San Francisco, Chicago, and other places in substantially the relative positions that they occupy upon the globe.

The fixed dial B is graduated as at B' to

represent minutes of time, as at B² to represent minutes of time, and as at B³ to represent hours of time. An hour-hand, E, is rigidly connected with the movable dial C, and 55 may be located upon the line of longitude of any desired place, preferably at the place at which the clock is in use. In this instance the hour-hand is rigidly connected with the movable dial and located on the line of longitude of Washington, D. C. A minute-hand, F, moves independently of the hour-hand and moving dial, and with said hour-hand indicates the minutes as the hour-hand does the hours upon the fixed dial B. 60

It is understood that the minute and hour hands above mentioned are those of an ordinary clock, and that they are to be operated by an internal mechanism exactly like any ordinary clock mechanism. Each of the local 70 dials C² is provided with a fixed hand, C³, and with a movable minute-hand, C⁴. A scale of degrees, B⁴, is arranged on the outer margin of the movable dial and on the inner margin of the fixed dial. This scale may serve to assist in estimating the time at places between and other than those represented by a local dial, C². A day-line, B⁵, is provided. The hour-dial is graduated into twenty-four divisions, and the fixed dial, as at B⁶, B⁷, B⁸, and 75 B⁹, indicates the morning, forenoon, afternoon, and evening, respectively. An opening, B¹⁰, exposes the indicating-figures of an interior calendar which is set for a new date, while an opening, B¹¹, on the fixed dial exposes the figures of a calendar showing the old date. Now, in order to correctly indicate the time at the several localities represented on the movable dial, it is necessary to establish a relative movement of the hour and minute hands of 80 each of the same with that of the main hand E, so that—as, for example, taking the local dial for Chicago—it shall indicate a time about one hour later than that indicated by the main hour-hand. 85

Referring now to Fig. 3, it will be seen that by the mechanism about to be described such relative movements of the main and local hour-hands and of the local minute-hands can be secured. Upon the movable dial C there 90 are mounted, by means of brackets G, pins H, in such manner as to be rotated, said

pinions being mounted upon the spindles, standards, or shafts H' , upon which each of the local minute-hands is secured. The pinion H has nine teeth. It has been stated that 5 the hour-hands of the local dial are fixed and move bodily with the movable dial and the main hour-hand, so that it is apparent that the local minute-hands must make one rotation while the main hour-hand and the movable dial move from one to the other of the several hour-indicating figures. This relative movement of the hands specified is accomplished by means of a gear, I , which has two hundred and sixteen teeth, and which is fixed 10 by screws I' to the cross-bar D . Now one revolution of the disk C will cause each of the pinions to travel once over the fixed gear I , thus producing twenty-four revolutions of each 15 of the minute-hands—that is, one revolution for each hour-space upon the fixed dial, of which there are twenty-four.

K represents the usual minute-wheel, and J the usual hour-wheel, of an ordinary system of clock-gearing, these being mounted upon a 20 spindle, L .

M represents an intermediate gear meshing with a pinion, K' , cut on the hub of the gear K . This system of gearing has its bearing in the frame D' and cross-bar D . The usual frictional contact between the hour and minute gears is maintained by a coiled spring, N , arranged on the shaft L .

The calendar devices employed each consist of a dial, O , mounted on a shaft, O' , carrying a ratchet, O'' , and a friction-disk, O''' , upon which a spring, O^4 , bears for the purpose of stopping a movement of the disk and ratchet caused by a pawl, P , which in this instance is extended, as shown by dotted lines 30 P' , to form a stop-arm, which falls upon a disk similar to the disk O'' , but arranged between the ratchet and the dial for the purpose of limiting the downward movement of the pawl. The pawl is formed on or secured to a pawl-lever, P'' , pivoted at P''' in the fixed dial, and in a cross-bar, Q , where also the ratchet and calendar-dial shaft is mounted for rotation. The free end of the pawl-lever P'' is curved and provided with a projection, as shown at 40 P^4 , (see Fig. 3,) which projection normally stands in a plane parallel with and at the rear of the movable dial C . Upon the latter is pivotally mounted a roller, R , having two peripheries, $R' R''$, the first—that is, the larger—being adapted during the rotation of the movable dial to come into contact with the projection P^4 of the pawl-lever, which operates the ratchet connected with the new-date-calendar dial, while the smaller periphery operates the pawl-lever and the other calendar-dial. The roller is located on the movable dial at a point directly under the day-line thereof, so that the calendars are operated at the lower or midnight hour of twelve, the old 50 date appearing in the quarter of the fixed dial marked "Evening," and the new date appearing in the quarter marked "Morning."

As the roller passes from the projections of the pawl-levers and beyond their pivots, it returns them to a position which causes the 70 pawl to take a new tooth in the calendar-ratchet, so as to rotate said ratchet at the next passage of the roller. The cross-bar D is cut away, as indicated by curved dotted lines, to permit the passage of the brackets G and 75 roller H between it and the dial.

The time required for the dial-lever-operating roller R to pass over the bottom levers is material, as its movements agree with that of the hour-hand, so that the old-date-calendar lever, 80 being operated by the smaller periphery of roller, does not change the indicated date on its dial until after the change of the date on the new-date calendar, and neither is changed at any other time than when the day-line of 85 the movable dial is at the bottom thereof. This line coincides with one of the twelve-o'clock marks, and there being two the calendar-dials will be changed only once in twenty-four hours. 90

From the above it will be seen that the date shown by the calendar-dial first moved is the "new date," while the date shown by the other calendar will be that of the day just passed.

Having described my invention and its operation, what I claim is— 95

1. In combination with the hour-hand of a clock, a fixed dial divided into twenty-four hour-spaces, a movable dial rigidly connected with said hour-hand and provided with local 100 dials, relatively arranged as described, and each having a fixed hour-hand and a movable minute-hand, a pinion mounted on the shaft of the minute-hand, and a fixed gear having a number of teeth proportioned to those of the 105 pinion as twenty-four is to one, substantially as specified.

2. In a clock of the character described, a fixed dial having twenty-four hour-spaces, in combination with moving dial, representing a 110 globe by lines of longitude, and having local dials arranged on the line of longitude of the localities indicated by said local dials, substantially as specified.

3. In a clock of the character described, the 115 combination of a fixed dial, having twenty-four hour-spaces, with the movable dial having a day-line, and a calendar-operating device located substantially on the day-line, with a calendar-operating pawl-lever, which projects 120 into the path of the calendar-operating device, mounted on the movable dial, substantially as specified.

4. The combination of a fixed dial, a movable dial carrying an hour-hand indicating 125 spaces on the fixed dial, and carrying a calendar-operating device, with calendars set one day apart, and having their operating pawl-levers projected into the path of the calendar-operating devices mounted on the movable 130 dial, substantially as specified.

5. The combination of a fixed dial, a movable dial having local dials thereon, a fixed gear, and pinions mounted on the movable dial

and operating the hands of the local dials, substantially as specified.

6. In a clock of the class described, a fixed dial having twenty-four hour-spaces and divided into quarters, indicating morning, forenoon, afternoon, and evening, and calendar-openings arranged, one in the morning quarter and the other in the evening quarter, in combination with mechanism moving with an

hour-hand employed to operate calendars indicating dates one day apart, substantially as specified.

In testimony whereof I affix my signature in presence of two witnesses.

SOLOMON S. MOYER.
